UNITED STATES PATENT OFFICE.

VICTOR E. RANDALL, OF BATTLE CREEK, MICHIGAN.

RAILWAY TIE.

Application filed October 26, 1920. Serial No. 419,608.

To all whom it may concern:

Be it known that I, VICTOR E. RANDALL, a citizen of the United States, residing at Battle Creek, in the county of Calhoun and State of Michigan, have invented certain new and useful Improvements in Railway Ties, of which the following description, taken in connection with the appended claims and accompanying drawing, forms 10 a specification.

This invention relates more particularly to railway ties made of concrete or analogous materials.

A characteristic feature of the present invention lies in connecting individual rail-bearing blocks or sleepers with metallic side rods having offset ends adapted to engage sockets within said blocks, in lieu of uniting said blocks by other means or forming a tie 15 for two or more rails in one homogeneous slab or sleeper.

It has been experienced that artificial stone railway ties made in one section carrying two rails deteriorate rapidly by the 20 pounding of rolling stock over them, owing to the rigidity of such ties and the meager facilities provided to overcome shock and vibration, as well as settling and heaving occasioned by freezing and thawing, and 25 also certain disregard for conditions that exist in many composite tie structures.

The present invention has among other objects to construct a tie having the desirable features of a wooden tie with the added 30 factors of safety, enduring stability, avoidance of clatter and jolt by rolling stock passing over them, neatness of appearance in a road bed, avoidance of dust and the spattering of mud by the ties not rising and 35 lowering in the passage of trains, together with a minimum of service required in keeping a roadbed in trim condition when equipped with ties of this nature.

A great object of the present invention 40 lies in forming the blocks comprising a tie, together with their connecting rods, so that a tie answering well for straight line traffic and the blocks of which can be connected at a minimum of expense may, by the 45 introduction of extra rods, be used on trackage requiring more stable foundation as, for instance, the rounding of curves.

Still another object of great advantage 50 lies in so forming the tie or side rods for connecting the rail blocks that the blocks may be placed in a roadbed and be easily

connected or detached, though the ties lie closely together.

Other objects and advantages are to simplify a tie, reduce the expense to produce 60 and add to its usefulness.

In the drawings forming a part of this specification, Figure 1 is a plan view of my improved railway tie.

Fig. 2 is a side view of the tie with its 65 lower connecting side rods removed.

Fig. 3 is another side view of the tie with the lower connecting side rods removed, and with rails attached to the tie sections, and shows one condition of relative settling of 70 the rail blocks.

Fig. 4 is a side view of a tie with all of its connecting side rods.

Fig. 5 is an end view of a tie with its connecting top side rods placed in a road- 75 bed trench, and shows the method of excavating to place or remove said rods.

Fig. 6 is a plan view of a rail block with wooden rail-bearing block inserts.

Fig. 7 is a vertical cross section on line 80 *i*—*i* of Fig. 6.

Fig. 8 is a plan view of a rail block with wooden rail-bearing block inserts, showing in dotted outlines a reinforcing structure of 85 metal.

Fig. 9 is a longitudinal side section of Fig. 8.

Fig. 10 is a vertical cross-section of a tie, taken on the line, as *a* of Fig. 9.

Like marks of reference refer to corresponding or equivalent parts in the different views in which A represents rail-bearing blocks, such as made of concrete or analogous materials; B and C, connecting side rods of metal; and D, rail attaching blocks 90 of resilient material—wood or its equivalent.

While it is not necessarily vital in the construction of a rail block that it be a parallelopiped in shape, generally they serve well for the desired purpose, and I have 100 illustrated this type of a rail block with which to show my improvements.

In moulding a rail block I form a series of sockets or holes, (as 1 and 2,) in the sides thereof and arrange said sockets at 105 either side of both the vertical and longitudinal centers of the block, and where four sockets are formed in the sides of a block, I prefer to arrange the same equidistant both from the ends and from the block bottom and top.

In general practice but two sockets on a

block side are necessary, but in all instances the sockets are directly opposite in the block sides.

In placing the rail-bearing blocks or tie sections in a roadbed, the blocks are laid so that the holes 1 will be near the upper outer ends of the blocks comprising a tie and into these holes the offset ends 3 of the connecting side rods B are inserted, a rod being fitted into either side of the blocks, similar but shorter rods C connecting the blocks near their bottom surfaces through the medium of the holes 2 aforesaid, the shorter rod engaging the sockets of the blocks at their inner ends.

It is preferable that when but one set of connecting side rods are used, the longer or upper ones be employed, as by use of these rods should a tie section settle from its opposite connection, either uniformly or inwardly inclined by reason of more stable outer block end support the block so settling would not increase the rail gauge and endanger the passage of rolling stock going thereto.

In making sharp curves and where the rolling stock is heavy and fast, it is expedient to use both the upper and under connecting rods, as all tendency of the rail blocks to separate is avoided and yet sufficient resiliency is provided in a tie to insure smoothness to rolling stock, and the avoidance of jolt and clatter that would ensue were a more rigid foundation used.

The sockets 1 and 2 in the tie sections do not of necessity extend from side to side thereof as that might induce a fracture or breaking line through a tie, and are of sufficient depth only to admit the shortened offset ends 3 of the side rods B and C to freely enter.

In the installation of tie renewals in old roadbeds, and especially in roadbeds where crushed stone is used for ballast, the present method of tie construction is of great importance for the reason that a trench of a depth and width to permit a rail section to be drawn into place will usually be sufficiently broad to permit a side rod to be installed after the blocks are in place, whereas, should bolts be used to connect rods placed on either side of a tie, great trouble would result not only from the amount of ballast to be removed but also from ties adjacent being in too close proximity to permit of such adjustments.

Side rods of the nature I have introduced not only permit of tie sections being readily connected, but they have the further advantage of being as readily removed and replaced. They require no extra bolts, necessitate no keys nor nuts to rust or be removed, and a filling-in of ballast thoroughly prevents their unseating from their places when once properly installed.

In Figs. 1, 6, 7, 8 and 9 are shown tie or rail bearing blocks having imbedded therein resilient rail attaching blocks of wood or equivalent material D. If of wood, these blocks are preferably impregnated with creosote or other weather nondeteriorating material and may be moulded within said tie blocks when the same are formed in appropriate moulds as shown (see Figs. 6, 7, 8 and 9) the rail attaching blocks D are disposed longitudinally within the upper face of the rail blocks or sleepers A, or in other words, are disposed transversely of the rail, and are spaced from one another in such a manner that the base of the rail may be allowed some range of sidewise adjustment to permit spikes to be driven into the rail attaching blocks. In Fig. 3, the rails are indicated at 5, the spikes at 6 and the rails are shown as resting not directly on the wooden members D, but on a plate 7 inserted between the rail base and said wooden blocks.

From the foregoing description, taken in connection with the drawing, it is believed the objects, advantages and general utility of my improved tie will be thoroughly understood.

What I claim as new and desire to secure by Letters Patent, is:

1. A railway tie comprising two rail-bearing blocks having holes in their sides, and metallic connecting rods having offset ends engaging within said holes and linking said blocks together.

2. A railway tie comprising two rail-bearing blocks having holes in their sides in directly opposite positions, and metallic connecting rods having offset ends engaging within said holes and linking said blocks together.

3. A railway tie comprising two blocks, said blocks having directly opposite sockets in their sides arranged diagonally between the corners of said blocks, side rods having offset ends engaging either block, longer rods engaging the upper outer sockets on either side of said blocks, and shorter rods engaging the lower sockets near the inner ends of said blocks on either side thereof.

4. A railway tie comprising two blocks having directly opposite sockets in their sides arranged diagonally between the corners of the blocks, side rods connecting said blocks on either side in parallel arrangement an upper set of said rods being longer than the under set, the under set arranged to connect said blocks by means of their inner end sockets, the upper set of rods connecting said blocks by means of their outer end sockets, all of said rods having offset ends engaging within said sockets, substantially as and for the purpose set forth.

5. A railway tie comprising two rail-bearing sections having holes in their sides

in directly opposite directions, one set of holes being diagonal from the other and at points equi-distant from the ends and the top and bottom of said blocks, said blocks 5 being spaced apart end to end with the holes near the tops of said blocks disposed outwardly from the spaced ends thereof, and metallic rods having offset ends engaging within said holes and linking said blocks together, corresponding holes of opposite blocks receiving the offset ends of a rod on each side of the block sections.

6. A railway tie comprising two rail-bearing blocks having directly opposite sockets 15 in their sides, one set of sockets being dia-

nal from the other and disposed at points equally distant from the ends and the tops and bottoms of said blocks, said blocks being arranged apart end to end, the lower holes of said blocks being inside of their centers 20 the upper holes thereof being outside of their centers, side rods having offset ends engaging said holes, a longer rod engaging the upper of said holes, a shorter rod engaging the lower of said holes, substantially as set forth.

VICTOR E. RANDALL.
